UNITED STATES PATENT OFFICE.

WILLIAM FRIESE-GREENE, OF BRIGHTON, ENGLAND.

AIR-CAR OR AIRSHIP.

1,031,705.

Specification of Letters Patent.

Patented July 9, 1912.

Application filed February 23, 1909. Serial No. 479,433.

To all whom it may concern:

Be it known that I, WILLIAM FRIESE-GREENE, of 203 Western road, Brighton, Sussex, England, photographer, have invented certain new and useful Improvements in and Relating to Air-Cars or Airships, of which the following is a specification.

This invention relates to air cars or air ships and has for its object to provide means whereby the car or ship may be maintained in equilibrium and on an even course.

An air ship or air car made in accordance with this invention is provided with two elongated gas bags and with one or more gyroscopes having their fly wheels disposed in the vertical plane in which the longitudinal axis of the car is disposed or planes parallel therewith and in some cases one or more gyroscopes having their axes in the vertical plane are provided. The gas bags may be disposed one above the other if desired.

Referring to the drawings, Figure 1 is a diagrammatic elevation of an air ship made in accordance with this invention in which the gas bags are disposed side by side; Fig. 2 is an end view:

25 *a a* are two gas bags disposed side by side and adapted to be inflated by hydrogen or other suitable gas.

30 *b* is a gyroscope having its spindle *c* disposed in the central vertical plane in which the longitudinal axis of the car lies; *d* is a second gyroscope having its spindle in the horizontal plane; *e* is a propeller; *f g* and *h* are motors for driving the gyroscopes and propeller; *j j* are horizontal members secured to the gas bags for supporting the 40 frame work *k k* of the car.

m is a vane pivoted on a horizontal pin *n*.
o is a rudder pivoted on a vertical pin *p*.

One of the gyroscopes *b* and the motor *f* are mounted on a platform *r* pivoted at *s* 45 so that they can be swung in a vertical plane by means of the cords *t* passing around a pulley *u* or by other suitable means.

Between the horizontal members *j j* is 50 disposed a wire or rod upon which is mounted a weight *q* which can be moved lengthwise of the vessel by any suitable means for the purpose of balancing or tipping the air vessel.

55 The frame forming and supporting the

car lies vertically below the centers of the bags and extends laterally of the longitudinal axis of the air ship to a width not greater than half the diameter of one of the bags.

60

In use one or both of the gyroscopes are kept spinning and great stability of the air ship is effected. The platform *r* is normally horizontal and the spindle of the gyroscope *b* is vertical. Should it be desired 65 to change the course of the air ship from one horizontal plane to another it may be effected by tilting the platform *r* so that the spindle *c* of the gyroscope *b* is inclined to the horizontal plane, the course of the 70 vessel in the vertical plane being modified more or less depending on the difference in the angle between the axis of the gyroscope and that of the airship. The course of the air ship can also be changed by movement 75 of the vane *m* and rudder.

What I claim and desire to secure by Letters Patent is:—

1. In air ships the combination of two 80 elongated gas bags and a gyroscope disposed so that its spindle lies in the same vertical plane as the longitudinal axis of the air ship, a platform pivoted in a horizontal plane for supporting said gyroscope, and means for applying force between said 85 platform and air ship whereby the air ship may be moved in the vertical plane around the spindle of the gyroscope and the inclination of the air ship in the horizontal plane thereby controlled, said gyroscope 90 acting as a fixed body against which force may be applied to move said air ship.

2. In air ships the combination of two 95 elongated gas bags and a gyroscope disposed so that its spindle normally lies in the same vertical plane as the longitudinal axis of the air ship, a platform pivoted in a horizontal plane for supporting said gyroscope, means for applying force between said platform and air ship whereby the air ship may 100 be moved in the vertical plane around the spindle of the gyroscope and the inclination of the air ship in the horizontal plane thereby controlled, said gyroscope acting as a fixed body against which force may be 105 applied to move said air ship, and a gyroscope with its spindle in a horizontal plane.

3. In air ships the combination of an 110 elongated gas field, and a gyroscope disposed so that its spindle lies in the same

vertical plane as the longitudinal axis of the air ship, a platform pivoted in a horizontal plane for supporting said gyroscope, means for applying force between said platform and air ship whereby the air ship may be moved in the vertical plane around the spindle of the gyroscope and the inclination of the air ship in the horizontal plane thereby controlled, said gyroscope acting as a fixed body against which force may be applied to move said air ship.

4. In air ships the combination of two elongated gas bags, a frame disposed vertically below the bags so that it extends laterally of the longitudinal axis of the air ship to a width not greater than half the diameter of one of the gas bags and a gyroscope disposed so that its spindle lies in the same vertical plane as the longitudinal axis of the air ship, and means for moving the

spindle of the gyroscope in the vertical plane.

5. In air ships the combination of two elongated gas bags, a frame disposed vertically below the bags so that it extends laterally of the longitudinal axis of the air ship to a width not greater than half the diameter of one of the gas bags, and a gyroscope disposed so that its spindle normally lies in the same vertical plane as the longitudinal axis of the air ship, and a gyroscope with its spindle in a horizontal plane.

In witness whereof, I have hereunto signed my name in the presence of two subscribing witnesses.

WILLIAM FRIESE-GREENE.
